UNITED STATES PATENT OFFICE

133,001

DESIGN FOR AN AIRPLANE

Daniel Spooner, Far Rockaway, N. Y.

Application November 13, 1940, Serial No. 96,536

Term of patent 7 years

To all whom it may concern:

Be it known that I, Daniel Spooner, a citizen of the United States, residing at Far Rockaway, New York, in the county of Queens and State of New York, have invented a new, original, and ornamental Design for an Airplane, of which the following is a specification, reference being had to the accompanying drawing, forming part thereof.

In the drawing

Fig. 1 is a side elevational view of an airplane showing my new design;

Fig. 2 is a front elevational view;

Fig. 3 is a top plan view;

Fig. 4 is a rear elevational view; and

Fig. 5 is a top and side perspective view thereof. In Figs. 2, 3 and 4 portions of the wing shown in dot and dash lines have been broken away for convenience of illustration.

The characteristic feature of my airplane design resides in the portion shown in full lines in the drawing.

I claim:

The ornamental design for an airplane, as shown and described.

DANIEL SPOONER.
